Automatic Conveyor Co., Cicero, Ill., a corpora-
tion of Illinois

Application October 19, 1929. Serial No. 400,750

7 Claims. (Cl. 198—233)

The present invention relates generally to portable conveyers which are adapted for use in moving coal, coke, ashes, crushed stone, sand, gravel, or other such material from a pile on the ground to a wagon or another conveyer. More particularly the invention relates to that type of portable conveyer which consists of an elongated angle-iron supporting frame, an endless conveyer element operating in and supported by the frame, a motor above the supporting frame having power transmitting mechanism for driving the conveyer element, and a rectangular wheel-equipped frame through which the angle-iron supporting frame extends and from which the supporting frame is supported by adjustable suspension means.

One object of the invention is to provide a portable conveyer of the type under consideration in which the rectangular wheel-equipped frame and the power unit consisting of the motor and the power transmission mechanism are so located or positioned with respect to the elongated angle-iron supporting frame that the conveyer balances properly and in such a manner that the receiving end thereof may be easily and readily picked up when it is desired to move the conveyer from one place to another.

Another object of the invention is to provide a portable conveyer in which the rectangular frame from which the supporting frame is suspended is equipped with a pair of wheels at the sides thereof and embodies an improved construction or arrangement whereby the wheels are mounted so that they may be swung at right angles from a position in which they are parallel to a position in which they are aligned and operate to permit the conveyer to be shifted bodily in a lateral direction.

Another object of the invention is the provision of mechanism which is associated with the rectangular frame and is operative to drive the wheels either conjointly or individually in either direction so as to facilitate movement of the conveyer into its operative position.

A further object of the invention is the provision of an improved sliding connection between the rectangular angle-iron supporting frame and the rectangular wheel-equipped frame which serves to guide the supporting frame during vertical adjustment thereof and prevents it from swaying laterally in the rectangular frame.

A still further object of the invention is to provide a portable conveyer which is efficient in operation and is generally of an improved character.

Other objects of the invention and the various advantages and characteristics of the present construction will be apparent to those skilled in the art from a consideration of the following detailed description.

The invention consists in the several novel features hereinafter set forth and more particularly defined by the claims at the conclusion hereof.

In the drawings which accompany and form a part of this specification or disclosure and in which like numerals of reference denote corresponding parts throughout the several views:

Figure 1 is a side elevation of a conveyer embodying the invention;

Figure 2 is a plan view, the cover of the power unit housing being omitted for purposes of illustration;

Figure 3 is an enlarged cross sectional view taken on the line 3—3 of Figure 1;

Figure 4 is a perspective view of the rectangular wheel-equipped frame, parts being omitted and shown in section;

Figure 5 is a vertical sectional view of the rectangular wheel-equipped frame, showing in detail the construction of the driving mechanism whereby the wheels may be driven either conjointly or individually; and

Figure 6 is a plan section of the rectangular frame.

The conveyer which forms the subject matter of the invention is adapted for use in moving coal, sand, gravel and other such material from a pile on the ground to a truck or second conveyer and comprises an elongated supporting frame 8. The latter is associated with a rectangular wheel-equipped frame 9 so that it may be properly positioned with respect to the material to be conveyed and may be moved from one place to another. The supporting frame 8 consists of a pair of sides, each of which embodies an upper longitudinally extending angle-iron bar 10, an intermediate angle-iron bar 11, and a lower angle-iron bar 12. These three bars are substantially parallel. They are spaced apart in vertical alignment and are secured to a plurality of longitudinally spaced angle-iron uprights 13 to form a rigid structure. The two sides of the supporting frame are held in horizontally spaced relation and cross connected by a plurality of angle iron cross bars 14 which are secured to the intermediate bars 11 and the uprights 13 (see Figure 1). The two sides of the supporting frame are also rigidly cross connected by a substantially imperforate plate 15, the side margins of which are bolted or riveted to the

horizontal and inwardly extending legs 12^a of the lower bars 12. This plate extends longitudinally throughout substantially the entire length of the supporting frame and overlies the 5 lower and return reach of an endless conveyer element which is in the nature of a belt 16. The upper bars 10 are arranged so that their horizontal legs 10^a are at the top and extend inwardly. The vertical legs 10^b of said bars 10 10 are bolted or riveted to the longitudinally extending legs 13^a of the uprights 13. The intermediate bars 11 are positioned in close proximity to the upper bars and are arranged so that their horizontal legs 11^a are at the bottom and 15 project inwardly in the same manner as the legs 10^a of said upper bars. The vertical legs 11^b of the intermediate bars are bolted or riveted to the legs 13^a of the uprights. The lower bars 12 are arranged similarly to the upper members 20 in that the horizontal legs 12^a thereof are at the top and the vertical legs 12^b are fixed to the legs 13^a.

The endless belt 16 which is preferably formed of leather or treated fabric is disposed between the sides of the supporting frame and is arranged so that the receiving end thereof extends around and is supported by a receiving end roller 17. The discharge end of the belt extends around and is supported by a delivering end roller 18. The upper reach of the conveyer belt is located between the upper and intermediate bars 10 and 11 and is carried by a longitudinal series of pulley or roller units. Each of these units comprises a central substantially cylindrical supporting roll 19 and a pair of troughing rolls 20. All three of these rolls are fixed to a shaft 21 which is journalled in a pair of bearing brackets 22. The latter are secured to the horizontal legs 11^a of the intermediate bars 11. The troughing rolls of the units are frusto-conical in form and operate to turn upwardly the marginal parts of the operative upper reach of the belt 16 so that said marginal parts are adjacent and in close proximity to the inwardly extending horizontal legs 10^a of the upper bars 10. By utilizing troughing rolls in connection with the roller units, the belt is supported so that the material tends to rest in the central portion thereof. The legs 10^a of the upper bars 10 together with angle-iron bars 23 which are secured to such legs prevent lateral displacement of the material over the side margins of the belt. The lower reach of the conveyer belt is disposed beneath the plate 15 and is supported upon a longitudinal series of roller-units, each of which consists of a pair of rolls 24. The latter are fixed to a transversely extending shaft 24^a which is journalled at the ends thereof in a pair of bearings 25. These bearings are supported from the vertical legs 12^b of the lower bars 12 by means of relatively short angle brackets 26. The ends of the plate 15 terminate adjacent to the rollers 17 and 18 respectively.

The roller 17 is fixedly secured to the central portion of a shaft 27, the ends of which are journalled in a pair of bearing brackets 28. These brackets fit against and are secured to the transverse legs 13^b of the two uprights 70 which are disposed adjacent to the receiving end of the belt-supporting frame 8. Said receiving end of the supporting frame embodies a pair of angle-iron members 30 which are cut and bent so that they are C-shaped in configuration. The ends of these members are secured to

the extreme ends of the upper bars 10 and the lower bars 12 respectively, by means of rivets or bolts which extend through the vertical legs of said bars. A receiving end top boot plate 32 extends across and is secured to the upper parts of the members 30 and a bottom boot plate 33 extends across and is secured to the lower parts of said members. The bottom boot plate extends rearwardly to the second pair of uprights 13 so that the portion of the return reach of the belt which is disposed in close proximity to the receiving end roller 17 will not contact with the material upon which the receiving end of the conveyer rests. To house additionally the receiving end of the supporting frame, pairs of plates 34 and 35 are provided. The plates 34 extend between the first and second pairs of uprights and are removably held in place by means of bolts 34^a which extend through the upper marginal portion of said plates 34 and the vertical legs 10^b of the upper bars 10. The plates 35 extend between the second and third pairs of uprights and are removably secured in place by bolts 35^a which extend through the vertical legs 10^b of the upper bars 10 similarly to 100 the bolts 34^a. A pair of plates 36 are arranged so as to form webs across the upper and lower parts of the end members 30 and to house or enclose in conjunction with the boot plates 32 and 33 the receiving end roller 17. 105

The conveyer belt 16 has angle-iron drag bars 16^a secured to the outer face thereof and is driven by an electric motor M which is disposed in a housing structure 37. The latter is positioned between the receiving end of the conveyer and the rectangular wheel-equipped frame 9 and is disposed above the conveyer belt. The driving connection between the motor M and the belt comprises a pinion 38 which is fixed to one end of the motor shaft m; a gear wheel 115 39 which meshes with the pinion 38 and is drivably connected to a shaft 40; a sprocket wheel 41 which is fixed to one end of the shaft 40 and is positioned outwardly of one of the frame sides; a sprocket 42 which is driven from the 120 wheel 41 by an endless chain 43 and is fixed to one end of a cross shaft 44; a sprocket wheel 45 which is fixed to the other end of the shaft 44 and is driven thereby and operates to drive a chain 46 at the other side of the supporting frame; and a sprocket wheel 47 which is driven by the chain 46 and is secured to the shaft 18^a upon which the delivering end roller 18 is mounted. The ends of the cross shaft 44 are mounted in bearing brackets 48 which are secured to a pair of the uprights 13 adjacent to the central portion of the supporting frame. An idler sprocket 49 is disposed between the sprocket wheels 45 and 47 and serves to support the central portion of the drive chain 46. This 135 idler sprocket is mounted on a cross shaft 50 which is journalled in bearing brackets 51. 130

The housing structure 37 for the motor is supported at the end adjacent to the receiving end of the conveyer by a pair of vertically extending angle-iron standards 53 and at the other end by a pair of vertically extending angle-iron standards 54. The lower ends of these standards are secured to the vertical legs of the angle-iron bars 10, 11 and 12 and the upper ends thereof are secured to the ends of and support a pair of longitudinally extending angle-iron bars 55. The standards 53 are somewhat longer than the standards 54, so that the bars 55 are inclined 140 downwardly toward the discharge end of the 150

conveyer. The standards 53 and 54 are preferably spaced apart so that the bars 55 extend at an angle of approximately 10°, this angle having been found in practice to best serve the various working requirements. A plate 56 extends transversely across the bars 55 and forms a base for supporting the electric motor M. The sides of the motor are housed or enclosed by means of plates 57 which are secured to angle-iron uprights 58. The latter project upwardly from and are secured to the longitudinal bars 55. A top or cover 59 is secured in place over the motor by bolts so that it may be removed when access to the motor is desired for repair or replacement purposes. The shaft 40 upon which the sprocket wheel 41 and the gear wheel 39 are mounted is journalled in bearing brackets 60 which are secured to two of the uprights 58.

The sides of the supporting frame are closed at the discharge or delivery end by a pair of plates 62 which are riveted or bolted to the vertical legs of the upper, intermediate and bottom bars 10, 11 and 12 of said frame. Notches 63 are cut in the outer ends of these plates 62 so as to form openings through which the ends of the delivering end roller shaft 18^a project respectively. The parts of said shaft which project outwardly of the plates 62 are journalled in a pair of bearings 64 which are mounted on the horizontal legs of a pair of longitudinally extending angle-iron bars 65. These last mentioned bars are secured at their inner ends to the rearmost uprights 13. The outer ends of the bars are riveted to a pair of rectangular plates 66 which are fixed to the outer ends of the plates 62.

The rectangular wheel-equipped frame 9 through which the belt-supporting frame 8 extends and from which said frame is suspended so that it may be moved vertically to position properly the discharge end of the belt 16, comprises a pair of ground wheels 70, the hubs of which are rotatably mounted on the outer ends of a pair of stub axles 71 at the sides of the wheel frame. These stub axles are pivotally connected to the ends of the horizontal leg 72^a of a transversely extending angle-iron crossbar 72 by means of king-pins 73 so that the wheels may be swung from their normal or parallel position into a position in which they lie in the same plane. In this last mentioned position of the wheels which is shown by dotted lines in Figure 2, the conveyer may be moved laterally so that the receiving end thereof may be properly arranged with respect to the pile of material to be conveyed. A pair of angle-iron arms 74 project from the ends of the crossbar 72 towards the receiving end of the belt-supporting frame 8. These arms 74 are connected to the crossbar by means of angle brackets 75. The latter are attached to the vertical leg 72^b of the crossbar and are secured by bolts 76 to the horizontal legs 74^a of the arms. The latter are at the bottom of the arms and project inwardly. Associated with said arms 74 is a pair of diagonally extending angle-iron braces 77. These braces are rigidly connected to the distal or outer ends of the arms 74 and project upwardly towards the discharge end of the belt-supporting frame 8. The central portions of the braces 77 are provided with a pair of lugs 78 to which are pivoted the front ends of a pair of angle-iron reaches or links 79. The rear ends of these links are pivotally connected by bolts 80 to a pair of bracket plates 81 which are fixedly secured to

the lower bars 12 adjacent to the standards 54. The links 79 serve to connect pivotally the lower end of the wheel frame to the supporting frame and are of such length that the wheels 70 are positioned beneath the central portion of said supporting frame. This arrangement operates to balance the conveyer so that the receiving end thereof may be easily and readily picked up and the conveyer moved from one place to another as desired. The plates 81 are each provided with a longitudinal series of bolt holes 81^a for use in arranging the links 79 in the proper or desired position. A pair of horizontally positioned triangular plates 82 are secured to the ends of the leg 72^a of the crossbar 72 and operate to form a supporting surface for the inner ends of the stub axles 71. These plates 82 are provided with holes through which bolts or other suitable locking devices may be inserted for securing the stub axles in their various assigned positions. The upper part of the wheel frame comprises a pair of vertically extending side members 83 and a top member 84. Each of the side members comprises a channel iron beam 85 and an angle iron beam 86 which are riveted or otherwise secured together and have their lower ends secured to a plate 87. Angle iron bars 88 are secured to the lower ends of the plates 87 and the horizontal legs 88^a thereof having openings or holes in which the upper ends of the king-pins 73 are mounted and held against lateral displacement. The outer marginal parts of the plates 82 are bent upwardly and then inwardly to form stops for preventing outward movement of the inner ends of the stub axles 71 when the latter are in parallel relation (see dotted lines in Figure 2) and the wheels are in the same transverse plane. The inwardly extending portions of the bent marginal parts of said plates 82 are riveted or bolted to the legs 88^a of the bars 88. The side members 83 are secured to the crossbar 72 by means of plates 89 which are riveted to the vertical leg 72^a of said crossbar and the vertical channel iron beams 85. The top member 84 consists of a pair of angle iron cross members 90 which are riveted to the upper ends of the beams 85 and 86 and to triangular brace plates 91. The beams 85 of the members 83 are arranged so that the transverse legs thereof project inwardly and form guideways 125 83^a. The upper ends of the diagonally extending braces 77 are riveted to the triangular plates 87 and are connected to the beams 86 of the members 83. The belt-supporting frame 8 extends between the side members 83 of the wheel-equipped frame 9 and is suspended or supported from above by means of a flexible cable 92. This cable is anchored at one end thereof to a bolt 93 which extends between and is secured to the cross members 90 of the top member 84. From the bolt 93, the cable extends downwardly and around a pulley 94 which is carried by the crossbar 95 of a bail 96. The ends of this bail are pivotally connected to a cross shaft 97 which extends through the belt-supporting frame and is mounted as hereinafter described. From the pulley 94 the cable 92 extends upwardly and around a pulley 98 which is carried by the top member 84. From pulley 98 the cable extends downwardly around a pulley 99 and then upwardly around a pulley 100. Said last mentioned pulleys are carried by the bail 96 and the top member 84 respectively similarly to the pulleys 94 and 98. From pulley 100 the cable ex- 150

- tends outwardly over a sheave 101 and then downwardly, along one of the side members 83 and around a winding drum 102. This drum is mounted on a shaft 103, the ends of which are rotatably mounted in bearing lugs 104 which are secured to a plate 105. The latter is riveted to the central portion of the adjacent side member 83. The drum is rotated so as to wind or unwind the cable by a worm gear 107. The latter is fixed to a shaft 108 which is mounted in a bearing bracket 109 and is operated by a crank 110. By rotating the drum so as to wind the cable thereon the belt-supporting frame 8 will be raised or elevated with respect to the ground wheels. By rotating the drum in the opposite direction, the cable will be lengthened so as to lower the supporting frame.
- The cross shaft 97 is non-rotatably held in a pair of brackets or lugs 111 which are secured to a pair of longitudinally extending angle bars 112 respectively. These bars underlie and are secured to the central portions of the intermediate bars 11. The ends of the shaft 97 are provided with loosely mounted shoes 113 which extend into and are slideable in the guideways 83a. These shoes form a sliding connection between the belt-frame and the wheel-frame which guides said belt-frame during vertical movement thereof and prevents it from swaying laterally.
- The structure 37 which houses the electric motor M is mounted approximately one-half way between the receiving end of the conveyer belt and the wheel-frame. By so positioning the structure, the conveyer normally assumes the position shown in Figure 1 and is so balanced that the receiving end thereof may be readily picked up when the conveyer is to be transported or moved from one place to another.
- To facilitate transportation of the conveyer and to permit of ready adjustment thereof into the desired position, mechanism is provided whereby the ground wheels 70 may be driven conjointly or individually. This mechanism is associated with the rectangular frame 9 and comprises a drive shaft 114 and a pair of pinions 115 and 116 which are mounted on the ends of the drive shaft and are adapted to cooperate with internal gears 117 on the felloes or rims of the wheels. The internal gears 117 are preferably made in sections or segments which are provided at the ends thereof with lugs 118. The latter are secured to the felloes or rims of the ground wheels by means of bolts 119. The pinions 115 and 116 are splined or otherwise connected to the drive shaft 114 so that they are rotatable with said shaft and are slideable longitudinally as hereinafter described into meshing relation with the internal gears 117. The drive shaft 114 is journaled in a pair of bearings 120 which are secured to the distal or outer ends of the angle-iron arms 74. Longitudinal displacement of the shaft relatively to the bearings is prevented by a collar 121 and a sprocket wheel 122. The latter are fixedly secured to the central portion of the drive shaft and are arranged so as to abut against the bearings 120. The drive shaft 114 is driven so as to cause rotation of the pinions 115 and 116 by means of a sprocket 123 and endless chain 124. The sprocket 123 is rigidly secured to the inner end of a transversely extending shaft 125. This shaft is rotatably mounted in a bracket plate 126 which is fixedly secured to the angle-iron beam 86 of one of the side members 83 and is positioned above

the adjoining ground wheel. The outer end of the shaft 125 is provided with a polygonal head 127 which is adapted to have applied thereto a crank 128. The chain 124 extends around the sprocket 123 and the sprocket wheel 122 and operates, during rotation of the crank 128, to impart rotary movement to the shaft 114. The pinion 115 is shifted longitudinally on the shaft 114 into and out of meshing relation with the internal gear 117 of the contiguous ground wheel by means of a lever 129. The latter extends vertically and is pivotally mounted at the lower end thereof on a pintle 130 which is carried by a bracket 131 on one of the bars 88. The lower end of the lever 129 is bent outwardly and embodies a finger 132 which cooperates with the bent portion of the lever to form a fork 133. The latter is connected by pins 134 to a collar 135 which is rotatably connected to the pinion 115. The upper end of the lever 129 is shaped to form a handle 136. When the lever is shifted in one direction, the fork 133 operates to shift the pinion 115 into mesh with the internal gear 117 on the adjoining ground wheel and thereby effects a driving connection between the drive shaft and said wheel. When the lever is shifted in the opposite direction, the pinion is caused to be shifted inwardly on the shaft 114 and out of mesh with the result that the adjoining ground wheel is free with respect to the driving mechanism. The pinion 116 is shifted longitudinally on the shaft 114 into and out of meshing relation with the internal gear 117 on the adjoining ground wheel that is opposite thereto by means of a lever 137 which is positioned in close proximity to the lever 129. The lower end of said lever 137 is pivotally mounted on the pintle 130 and is bent forwardly to form an arm 137a. This arm is pivotally connected by a bolt 138 to one end of a shifter bar 139. The other end of the shifter bar is pivotally connected to the central portion of an arm 140 which is pivotally connected to one of the brackets 75 and embodies a fork 141. This fork is connected by pins 142 to a collar 143 which is rotatably connected to the pinion 116. When the lever 137 is shifted in one direction, the shifter-bar together with the arm 140 and the fork 141 operates to shift the pinion 116 into mesh with the internal gear 117 of the adjoining ground wheel 125 and effects a driving connection between said wheel and the drive shaft 114. When the lever 137 is shifted in the opposite direction, the pinion 116 is caused to be shifted inwardly on the shaft and out of mesh. The pinions 115 and 116 together with the various operating parts that are associated therewith exemplify means whereby the ground wheels may be driven either conjointly or individually. The inner portions of the pinions 115 and 116 are provided with annular flanges 144 which operate to prevent them from being shifted outwardly past the internal gears 117. These flanges are preferably formed integrally with the pinions and are adapted to engage the inner side faces of the internal gears.

The operation of the conveyer mechanism will be as follows: The ground wheels 70 which are normally in parallel relation, as shown by full lines in Figure 2, permit the conveyer to be moved so that the receiving end thereof rests upon or adjacent to the material that is to be elevated or conveyed. If desired, the ground wheels may be driven for conveyer moving purposes, first by manipulating the levers 129 and 137 so as to effect engagement of the pinions

- 115 and 116 with the internal gears 117 and then turning the crank 128 in the proper direction to cause drive of the shaft 114 through the medium of the chain and sprocket connection.
- 5 In the event that it is necessary to shift the conveyer angularly in order to position the receiving end properly with respect to the material, one of the pinions is shifted into meshing relation and the other pinion is shifted out of mesh and then the crank 128 is turned to effect rotation of the power driven wheel. By applying power to one of the wheels and not the other, it is manifest that the conveyer will be turned about the loose wheel and caused to be rotated or shifted angularly. To start the conveying operation, the electric motor M which is usually supplied with current from an overhead trolley system or connector, is started so as to drive the conveyer belt 16 through the medium of the chains 43 and 46 and the various sprocket wheels that are associated therewith. During drive of the belt, the material is shoved onto the receiving end of the supporting frame 8 where it is engaged by the drag bar 16^a and propelled to the discharge end of the conveyer. In the event that it should be desired to move the conveyer transversely or laterally, the ground wheels 70 are swung 90° so that they are positioned in longitudinal alignment. In this position of the wheels the conveyer may be shifted bodily in a lateral direction. To adjust the height of the discharge end of the conveyer, it is only necessary to turn the cable drum 102 to effect the necessary adjustment. During such adjustment, the shoes 113 travel in the guideways 83^a of the side members 83. At the conclusion of the conveying operation, the conveyer may be shifted into a horizontal position by raising the discharge end and while in such position moved away.
- The conveyer disclosed herein is exceedingly efficient in operation by virtue of the fact that provision is made for driving the ground wheels conjointly or individually and the various operating parts thereof are so housed and positioned that the material to be conveyed can not injure the working thereof.
- The invention is not to be understood as restricted to the details set forth, since these may be modified within the scope of the appended claims, without departing from the spirit and scope of the invention.
- This application constitutes in part a division of an application filed September 20, 1928, Serial No. 307,109.
- Having thus described the invention, what I claim as new and desire to secure by Letters Patent, is:
1. In a portable conveyer, the combination of an elongated supporting frame comprising sides, an endless conveyer means extending between the sides and from one end of the frame to the other, mechanism for operating the conveyer means, carried by the supporting frame, a substantially vertical, rectangular frame through which the supporting frame extends, a pair of ground wheels, a pair of stub axles on the extreme outer ends of which the wheels are mounted, king pins extending through the central portion of the stub axles and mounted adjacent to the lower ends of the side members of the rectangular frame so as to permit the wheels to be swung from a normal parallel position into a position wherein they are in longitudinal alignment and permit the conveyer to be moved laterally, and a pair of substantially horizontal plates connected to the ends of the lower cross-bar of the rectangular frame and adapted to support and form bearing surfaces for the inner ends of the stub axles, the outer parts of the plates being bent upwardly to form stops for engaging the inner ends of the stub axles when said axles are in the position wherein the wheels are aligned one with the other. 80
2. In a portable conveyer, the combination of an elongated supporting frame comprising sides, an endless conveyer means extending between the sides and from one end of the frame to the other, mechanism for operating the conveyer means, carried by the supporting frame, a substantially vertical, rectangular frame through which the supporting frame extends, a pair of ground wheels, a pair of stub axles on the extreme outer ends of which the wheels are mounted, king pins extending through the central portion of the stub axles and mounted adjacent to the lower ends of the side members of the rectangular frame so as to permit the wheels to be swung from a normal parallel position into a position wherein they are in longitudinal alignment and permit the conveyer to be moved laterally, a pair of substantially horizontal plates connected to the ends of the lower crossbar of the rectangular frame and adapted to support and form bearing surfaces for the inner ends of the stub axles, the outer parts of the plates being bent upwardly and then inwardly to form stops for engaging the inner ends of the stub axles when said axles are in the position wherein the wheels are aligned with one another, and bars connected to the inwardly bent parts of the plates and arranged so as to overlie the central portions of the axles and support the upper ends of the king pins. 85
3. In a portable conveyer, the combination of an elongated supporting frame, an endless conveyer means supported by the frame and extending between the sides thereof, a substantially vertical, rectangular frame adjacent to the central portion of the supporting frame and through which the latter extends, said rectangular frame having ground wheels and embodying side members provided with vertical guideways, a pair of shoes pivotally supported at opposite sides of said central portion of the supporting frame and mounted slidably in said guideways in order to form sliding connections between the two frames, and mechanism for raising and lowering the supporting frame, mounted on said rectangular frame. 90
4. In a portable conveyor, the combination of an elongated supporting frame, an endless conveyer means supported by said frame and extending between the sides thereof, a substantially vertical, rectangular frame adjacent to the central portion of the supporting frame and through which the latter extends, said rectangular frame being provided with ground wheels and comprising a top member and side members having vertical guideways, a transverse shaft extending through the supporting frame and having shoes connected pivotally to the ends thereof and mounted slidably in the guideways to form sliding connections between the two frames, a bail connected to the supporting frame, and adjustable supporting means between said bail and the top member of the rectangular frame. 95
5. In a portable conveyer, the combination of an elongated supporting frame, an endless conveyer means supported by said frame and extend- 100

ing between the sides thereof, a substantially vertical, rectangular frame adjacent to the central portion of the supporting frame and through which the latter extends, said rectangular frame being provided with ground wheels and comprising a top member and side members having vertical guideways, a transverse shaft extending through the supporting frame and having shoes at the ends thereof mounted slidably in the 10 guideways to form sliding connections between the two frames, a bail having the ends thereof pivotally connected to said shaft, and adjustable suspension members between the bail and the top member of the rectangular frame.

15 6. In a portable conveyer, the combination of an elongated frame, an endless conveyer means carried by the frame and extending from one end thereof to the other, a substantially vertical, rectangular frame positioned adjacent to the central portion of the elongated frame and through which the latter extends, a pair of laterally spaced ground wheels for supporting conveyer, said wheels being associated with the lower ends of the side members of the rectangular 20 frame and embodying internal gears around the rims thereof, and mechanism for manually driving the wheels mounted on and supported by the rectangular supporting frame, and comprising a rotatable horizontally extending shaft supported adjacent to the lower crossbar of the rectangular frame, a pair of pinions mounted on the ends of the shaft and arranged to mesh with the internal gears on the wheels, and a hand-

crank associated with one of the side members of the rectangular frame and connected to drive the shaft.

7. In a portable conveyer, the combination of an elongated frame, an endless conveyer means 80 carried by the frame and extending from one end thereof to the other, a substantially vertical, rectangular frame positioned adjacent to the central portion of the elongated frame and through which the latter extends, a pair of laterally spaced ground wheels for supporting conveyer, 85 said wheels being associated with the lower ends of the side members of the rectangular frame and embodying internal gears around the rims thereof, and mechanism for manually driving the 90 wheels in either direction and conjointly or individually, comprising a rotatable, horizontally extending shaft mounted on the rectangular frame so that it is arranged in close proximity to the lower crossbar, a pair of pinions mounted on and 95 connected to be driven by the ends of the shaft and shiftable into and out of mesh with said internal gears, a hand crank supported on the central portion of one of the side members of the rectangular frame and connected to drive the 100 shaft, and levers for individually shifting the pinions into and out of mesh with their respective internal gears extending alongside of the 105 said one side member of the rectangular frame and operable from a point adjacent to the hand crank.
